TOOL SHARPENER.

James Boyd Anderson, Winchester, Ky.

Application August 7, 1935, Serial No. 35,182

8 Claims. (Cl. 51—205)

This invention relates to tool sharpeners of that general class shown and described in my co-pending application, filed in the U. S. Patent Office on the 14th day of June, 1934, bearing Serial Number 730,670, the present invention being an improvement thereon.

The object of the invention is generally to improve and increase the utility and efficiency of the tool by providing means whereby the abrading element may be quickly and conveniently adjusted at different angles with respect to the tool supporting surface to accommodate tools having different angular cutting edges without changing the position of the abrading holder with respect to said supporting surface.

A further object of the invention is to provide a scissors sharpener having an abrasive carrier mounted for oscillation within the holder and provided with means whereby the carrier may be clamped at the desired position of adjustment within the holder.

A further object is to provide a novel form of clamping device which serves a dual function of simultaneously holding the abrading element within the carrier and clamping said carrier within the holder.

Further objects and advantages are set forth in the accompanying specification.

In the accompanying drawing forming a part of this specification and in which similar numerals of reference indicate corresponding parts in all the figures of the drawing,

Figure 1 is a side elevation of a tool sharpener embodying the present invention and showing the manner of using the same.

Figure 2 is a top plan view.

Figure 3 is a transverse sectional view taken on the line 3—3 of Figure 2.

Figure 4 is a vertical sectional view taken on the line 4—4 of Figure 3.

Figure 5 is a transverse sectional view showing a modified form of clamping screw.

The improved scissors sharpener, forming the subject-matter of the present invention, comprises a solid body portion 5 preferably substantially rectangular in shape, as shown, and formed of metal, bakelite, or other suitable material. Extending from the upper portion of the body 5 and preferably integral therewith is an overhanging hook-shaped member constituting a holder 6, the free end 7 of which is spaced from the tool supporting surface 8 of the body, as shown. The holder 6 is provided with a cylindrical seating recess 9 opening through the opposite ends thereof and in which is mounted for

oscillation a correspondingly shaped abrasive carrier 10. One side of the carrier 10 is formed with a flat face 11 and opening through said flat face is a substantially rectangular recess 12 adapted to receive a block of abrasive material, indicated at 13. The holder 6 near the hooked end thereof is provided with a slot 14 and operating in said slot is a clamping screw 15, one end of which is provided with a finger piece 16, while the other end thereof is threaded in an opening 17 in the carrier with the flat terminal 18 of the screw bearing against the adjacent surface of the abrasive block, as best shown in Figure 3 of the drawing. Each end of the abrasive carrier is stamped or otherwise formed with a pointer 19 adapted to register with graduations or numerals 20 formed on the holder 6 for indicating different positions of adjustment of the abrading element with respect to the tool supporting surface 8 of the body.

It will here be noted that the clamping screw 15 serves the dual function of holding the abrading element 13 within the carrier and clamping the carrier in a set position within the holder. Furthermore, the finger piece 16 provides a convenient means for oscillating the abrasive carrier within its seat when adjusting the abrading element to accommodate scissors or other tools having different angular cutting edges. The body 5 at its junction with the holder is formed with a relatively deep depression 21 adapted to receive the forefinger while the side walls of the body may be formed with shallow recesses to receive the thumb and middle finger of the user.

In operation, the sharpener is grasped between the fingers in the manner shown in Figure 1 of the drawing and said sharpener positioned over one of the blades of a pair of scissors, indicated at 22. The clamping screw 15 is then loosened and the carrier, together with the abrading block, adjusted within the holder until the active face of the block of abrasive material coincides with the bevel or inclination of the cutting edge of the scissors blade after which the clamping screw is tightened which holds the abrading block against displacement and firmly clamps the carrier against the walls of its seat in the holder. The tool is then reciprocated longitudinally of the scissors blade in the usual manner until the cutting edge thereof is sharpened to the desired degree. It will here be noted that the tool supporting surface 8 overhangs the seat 9 and intersects the active surface of the abrading block at one side of the medial line thereof so that should one portion of the abrading block be

come unduly worn, said abrading block may be removed from the carrier and replaced therein in a reverse position so that a fresh abrasive surface will be presented to the cutting edge of the 5 tool to be sharpened and this applies to each of the angular faces of said abrading block.

In Figure 5 of the drawing there is illustrated a modified form of clamping device in which the clamping screw 23 is provided with a lock nut 10 24 which bears against the holder and serves to lock the carrier in adjusted position.

It will, of course, be understood that the tool 15 sharpeners may be made in different sizes and shapes and formed of any suitable material without departing from the spirit of the invention. It will also be understood that while the tool sharpener is especially designed for sharpening scissors, said tool may be used with equally good results for sharpening any kinds of edged tools.

Having thus described the invention, what is claimed as new is:

1. A tool sharpener comprising a body, a holder mounted on the body, a carrier mounted for oscillation within the holder, a sharpening element seated in the carrier, and means extending through the walls of the holder and carrier and engaging the sharpening element for simultaneously clamping the sharpening element within the carrier and the carrier within said holder.

2. A tool sharpener comprising a body having an overhanging hook integral therewith and constituting a holder, said holder being provided with a slot and formed with a substantially cylindrical seat, a correspondingly shaped carrier mounted for oscillation within said seat, a sharpening element fitted in the carrier, and means extending through the slot in the holder and through said carrier and engaging the sharpening element for clamping the sharpening element within the carrier and the carrier within its seat.

3. A tool sharpener comprising a body having a tool supporting surface and provided with a hook-shaped portion constituting a holder, the free end of which is spaced from the tool supporting surface, said holder being formed with a slot and having a substantially cylindrical seating recess therein, a carrier mounted for oscillation within said seat, a sharpening element mounted in the carrier and having one face thereof exposed at the tool supporting surface, and means extending through the slot in the holder and through the carrier and engaging the sharpening element for clamping the parts in adjusted position.

4. A tool sharpener comprising a body having a tool supporting surface and provided at one end with an overhanging holder spaced from said tool supporting surface and provided with a substantially cylindrical seat, a substantially cylindrical carrier mounted for oscillation within the seat and having one side thereof flat and formed with a recess, a sharpening element disposed in said recess and having one face thereof disposed at the tool supporting surface, and a clamping screw extending through the slot in the holder

and through said carrier and engaging the sharpening element.

5. A tool sharpener comprising a body having finger receiving recesses and provided with a tool supporting surface, a substantially hook-shaped holder projecting from one end of the body with its free end spaced from the tool supporting surface, said holder being formed with a vertical slot and having a substantially cylindrical seating recess formed therein and opening through opposite ends of the holder, a carrier mounted for oscillation within said seating recess, a sharpening element fitted in the carrier, a clamping screw extending through the slot in the holder and through said carrier and engaging the sharpening element for holding said sharpening element at different positions of angular adjustment with respect to the tool supporting surface, and an indicator mounted on the carrier and cooperating with indicia on the holder for indicating the position of angular adjustment of the sharpening element.

6. A tool sharpener comprising a body having finger receiving recesses and provided with a flat tool supporting surface, said body being formed with an integral overhanging hook-shaped holder, the free end of which is slotted and spaced from the tool supporting surface, said holder having a seating recess formed therein, a carrier mounted for oscillation in the seating recess and provided with a recess opening through the opposite ends thereof, an abrading block insertable in said recess from either end of the carrier, and a clamping screw extending through the slot in the holder and through said carrier and engaging the abrading block, the tool supporting surface intersecting the adjacent surface of the abrading block at one side of the medial line thereof.

7. A tool sharpener comprising a body having a tool supporting surface and provided with a substantially hook-shaped holder, the free end of which overhangs and is spaced from the tool supporting surface, said holder being provided with a vertical slot and formed with a seating recess, a carrier mounted for oscillation within the seating recess, and an abrading element fitted in the carrier and having one face thereof exposed at the tool supporting surface, and a clamping screw extending through the slot in the holder and having one end thereof provided with a finger piece and its other end threaded through the carrier and bearing against the abrading element.

8. A tool sharpener comprising a body, an overhanging holder mounted on the body and provided with a transverse slot and having a seating recess communicating with said slot, a carrier mounted for oscillation within the seat, a sharpening element fitted in the carrier, a clamping screw extending through the slot and carrier and engaging the sharpening element, and a lock nut threaded on the clamping screw and adapted to bear against the holder for locking the carrier in a set position.
